AUXILIARY WATER HEATER

Filed Aug. 9, 1926

Witness:
Chas. L. Koursh.

UNITED STATES PATENT OFFICE.

JOHN EDWARD ERCANBRACK, OF CHICAGO, ILLINOIS.

AUXILIARY WATER HEATER.

Application filed August 9, 1926. Serial No. 128,188.

My present invention relates to the provision of an auxiliary water heater particularly adapted for attachment to boilers employed either for the heating of the premises or the production of steam for other purposes. As will hereafter be seen my auxiliary water heater is so constructed that attachment is made to the boiler at two separated points both below the water level of the 10 boiler and is arranged to provide a continuous pitch in the circulation from the boiler through the heating tubes in the tank and back to the boiler. A part of the circulation from the boiler is enclosed in a hot 15 water storage tank connected both with the water service supply pipe and the service distribution system of the premises to be supplied with hot water whereby the water passing from the service supply pipe through 20 the storage tank will be heated in the tank by the circulation from the boiler.

I also arrange a connection for the return of the main boiler system, that is, after it has performed the work for which it was primarily intended, with the header leading to the tank circulation whereby the drain on the boiler is reduced and the heat which remains in the condensation and return is utilized under normal conditions for the 30 heating of the water supply in my auxiliary heater. In order to effect the above arrangement I have had to provide means to prevent the flow from the boiler and the flow from the boiler return from interfering or 35 blocking each other.

In the carrying out of my invention I have designed a head for the tank with which the boiler makes connection, which has a large capacity of flow and is easily opened for 40 purposes of clean out or repair.

The pitch of the circulation of water to the auxiliary heater from and back to the boiler is of great importance because while the difference in weight of cool and heated 45 water is enough to create a circulation, the pitch by reason of its abruptness or otherwise, effects the rapidity of the circulation and thereby the efficiency of the auxiliary heater and also permits me to utilize effectively the return from the boiler system as an effective source of heat.

I have attained the above mentioned ob-

jects and secured the above referred to results by means of the structure illustrated in the accompanying drawings, in which:—

Fig. 1 is a plan of a boiler with my auxiliary water heater connected therewith.

Fig. 2 is a front elevation of the structure shown in Fig. 1.

Fig. 3 is a side elevation of the structure shown in Figs. 1 and 2, and

Fig. 4 is a fragmental section of a tank and head with which head the boiler connections are made.

Similar reference characters refer to similar parts through the respective views.

The main boiler illustrated is of the conventional fire box type consisting of the forward or body portion, 1, in which is the fire box, 2, which main body portion rests on an ash pit structure, 3. Extending rearwardly from the main body portion, 1, of the boiler is the tube portion, 4. Upon one side of the main body portion, 1, of the boiler and below the normal water line of the boiler is provided a bored and tapped embossment, 5, which may be secured to the boiler in accordance with any known practice of making such connections. Boilers of the type herein illustrated have usually provided therein, at a point on the back of the main body portion, 2, just below the tube portion, 4, a like embossment, 6, with which it is the present practice to make connection to the return of the main system to which the boiler is attached.

My auxiliary water heater consists of a heating and storage tank, 7, which I have illustrated as of the horizontally disposed type. The tank, 7, is provided with bored and tapped embossments, 8 and 9, through which respectively are made the connections for the service water supply to the tank and the supply to the premises to be served with hot water.

In what may be regarded as the front end of the tank, 7, and in the lower portion thereof is provided an aperture, 10, of sufficient extent to admit the number of tubes necessary for heating the tank of the required capacity. I have shown the end plate of the tank about the aperture, 10, as flat and against the flat portion of the head of the tank surrounding the aperture 10 is placed a

suitable gasket, 11, against the outer face of which abuts a tube plate, 12. The tube plate is provided with perforations as is usual to tube plates in which tubes 13 are inserted and headed over.

I have shown particularly in Fig. 2 three vertical ranks of such tubes, each vertical rank comprising two U tubes. The pitch, as shown in Fig. 3, is carefully maintained in 10 the tubes 13 so that the auxiliary circulation from and to the boiler will readily relieve itself of air liberated from the water.

Around the face at the periphery of the tube plate 12 is another gasket 15 and secured 15 against the gasket 15 is the header casing 16. The means of securing these parts together are preferably stud bolts 17 on the outer ends of which are screwed nuts 18. Running horizontally across the header casing 16 and between the upper and lower six tube groups of pipes is a partition 19, dividing the header into an upper chamber 20 and a lower chamber 21. From either side of the upper chamber 20 are provided suitable 20 threaded pipe connections 22 and 23 respectively. From the bottom of chamber 20 leads a suitable pipe connection 24.

The front of the casing 16 is open to afford access to chambers 20 and 21 and these openings are closed by a face plate 25 secured in position by headed bolts 26. Connection is made through pipe 27 running from embossment 5 to the pipe connection 22 and the tank is so set with relation to the boiler that 30 this pipe 27 is given the desired downward pitch from the boiler to the tank connection. Connection is also made between the threaded embossment 6 on the boiler and the pipe connection 24 on the head which is so 35 proportioned by the disposition of pipe or pipes 28 as to provide a downward pitch from the head 16 to the connection 6 of the boiler.

I have indicated the return from the main boiler system to the head through the pipe 29 which makes connection with the pipe connection 23 on the head which is just opposite to the connection from the upper portion of the boiler and to prevent the return 50 through pipe 29 from interfering with the flow from the boiler I provide the baffle 30, which extends from the face plate 25 sufficiently far into the chamber 20 so as to interfere with a direct flow between the openings 22 and 23.

The details of the internal circulation of boilers are not always thoroughly understood but the principles controlling such a circulation are well known. That is, the 60 gravitation or falling of the cooler bodies of water in the boiler force the hotter bodies of water in immediate contact with the heating surfaces upwardly to the top of the boiler, and it is further known that the rapidity of 65 the internal boiler circulation effects the

amount of heat, or number of B. t. u.'s, absorbed by the water from the heating surfaces.

The phenomenon of the rising and falling of the water in the boiler in accordance with 70 its difference of temperature in connection with the pitch of the boiler circulation through the auxiliary tank will insure a moderate flow of heated water through the tubes 13 in the tank at all times. But when the 75 water in the tank outside of tubes 13 is colder than the boiler water, both the auxiliary circulation through the tank and the internal circulation through the boiler will be accelerated. This improves the internal circulation 80 of the boiler and increases the absorption of heat therein.

It will also be noted that the return connection from the main boiler system is made through pipe connection 23 with the 85 head 16, and this condensation helps materially to supply the heat extracted in the auxiliary tank so that when but little water is being drawn from the tank, the return supplies about all the heat that is required to 90 keep the supply of water in the tank at the desired temperature. Not only do I utilize the heat in the return from the main boiler system, but by attaching this return at a point where a circulation is normally taking 95 place, the interior circulation of the boiler is not only accelerated but the exterior boiler circulation is also rendered more uniform and constant and subject to less fluctuation.

In warm weather where the main boiler, if 100 employed for heating, would be run very low, the absorption in the auxiliary boiler is not excessive, but under normal operation the increase in internal boiler circulation and the steadyng of the external boiler circulation 105 is so helpful to the operation of the main boiler that the absorption of heat in the auxiliary water heater is substantially without additional cost.

Having described my invention, what I 110 claim as new and desire to secure by Letters Patent, is—

1. In combination with a boiler a tank having inlet and outlet ports therein and provided with an aperture in one end near the bottom thereof, a tube plate registering with said aperture, U tubes in vertical ranks extending from said plate through said aperture into said tank, an exterior head provided with upper and lower chambers with 115 which the upper and lower ends of said tubes respectively communicate, ports upon opposite sides of said upper chamber and a single port in the bottom of said lower chamber, a conduit establishing communication 120 between said boiler and one of the ports in said upper chamber, a conduit establishing communication between the port in said lower chamber and said boiler and a return pipe from the primary circulation of said 125 130

boiler to the other port of said upper chamber.

2. In combination with a boiler a tank having inlet and outlet ports therein and provided with an aperture in one end near the bottom thereof, a tube plate registering with said aperture, U tubes in vertical ranks extending from said plate through said aperture into said tank, an exterior head provided with upper and lower chambers with which the upper and lower ends of said tubes respectively, communicate, ports upon opposite sides of said upper chamber and a single port in the bottom of said lower chamber, a conduit establishing communication between said boiler and one of the ports in said upper chamber, a conduit establishing communication between the port in said lower chamber and said boiler and a return pipe from the primary circulation of said boiler to the other port of said upper chamber, and a baffle in said upper chamber between the respective ports thereof.

3. A water heater comprising a boiler, an

auxiliary boiler water circulation consisting of tubes leading from and returning to said boiler and including a series of heat transfer tubes located wholly below the water level of said boiler and inclined from one end to the other thereof, a storage tank surrounding said heat transfer tubes and having inlet and outlet ports therein, and a primary exterior boiler circulation consisting of tubes the return whereof communicates with and includes said heat transfer tubes. 25 30 35

4. A water heater comprising a boiler, an auxiliary boiler water circulation consisting of tubes leading from and returning to said boiler and including a series of heat transfer tubes located wholly below the water level 40 of said boiler, a storage tank surrounding said heat transfer tubes and having inlet and outlet ports therein, and a primary boiler circulation consisting of tubes, the return whereof communicates with and includes said heat transfer tubes. 45

JOHN EDWARD ERCANBRACK.
